UNITED STATES PATENT OFFICE

2,370,041

MACHINE TOOL

John Jasionowski, Hartford, Conn.

Application September 10, 1942, Serial No. 457,865

4 Claims. (Cl. 51—95)

My invention relates to machine tools.

In the use of such tools as external grinders, difficulty has heretofore been experienced with wear at the opposite ends of the under, or bed, frame on which the work support is reciprocably mounted. This wear results from the displacement of the weight during the alternate movements of the work support to opposite ends of the bed frame, and the heavier the work piece being operated upon, the greater has been the wear at these opposite ends. Further, this wear is also increased by the entry of dirt and other abrasive material between this frame and the work support slidable thereon, and results in the wearing off of sloping end portions. When thus worn off at the ends, unless the under frame or bed is scraped in such manner as to return its top surface to its proper flat form, the grinder is incapable of further accurate work. Further, the scraping operation is a time consuming and expensive one, necessitating the grinder being out of use for a substantial period, and such a scraping operation is moreover one which is only capable of being performed by specially skilled mechanics.

My invention has among its objects to provide an improved construction whereby such wear upon the ends of the under frame of a tool including such a reciprocable element, is eliminated. My invention also has among its objects to provide an improved work feeding means for a grinder or other like machine, whereby the previous difficulty with wearing off such sloping portions is overcome, and, more particularly, to provide such improved feeding means having improved movable supporting means for the work support which maintain the latter adequately supported in all longitudinal positions of the same in such manner as to prevent such excessive wear at the ends of its travel. A further object of my invention is to provide such improved work support supporting and feeding means comprising improved oscillating rolls or supporting members for the work support which travel with the latter during its longitudinal movement. Other objects are to provide such improved rolls adapted to provide an adequate extensible support for the work support in all positions thereof in such manner as to eliminate the previous difficulty with heavy overhanging weight at the ends of its travel, and further to provide such rolls which are so movable relative to the work support as in all different positions of the rolls to continue to support the work support both adjacent its ends and at diametrically opposite points on the oscillating

rolls. A still further object of my invention is to provide such an improved construction wherein the length of the machine required for a given travel of the work support is substantially decreased as compared with existing grinders. Other objects include the provision of an improved mechanism having the advantages aforesaid and having improved controlling mechanism for the several mechanisms of the tool or grinder, disposed in an improved manner relative to such rolls, and also to provide such an improved machine which is also capable of being inexpensively manufactured, has long life in service, and requires less power to operate it and a minimum of oiling. These and other advantages of my improvements will, however, hereinafter more fully appear.

In the accompanying drawing, I have shown for purposes of illustration one embodiment which 20 my invention may assume in practice, the same, while not limited thereto, being shown as applied to use in an external grinder.

In this drawing:

Figure 1 is a side elevation partially in section 25 showing my improvements applied to a standard type of external grinder, the parts being shown in their mid-position;

Fig. 2 is an end elevation partially in section on line 2—2 of Figure 1;

Fig. 3 is a view similar to Figure 1 but of only the upper part of the machine and with the rolls shown in full and dotted lines in extreme positions thereof and of the work support, and

Fig. 4 is a detail perspective view of one of the 35 rolls.

In this illustrative construction, I have shown my invention applied to a grinder having a usual main grinding wheel 1 and smaller grinding wheel 2, both suitably adjustable on a bed 3 relative 40 to a usual support 4 on the main or bed frame 5 of the machine and relative to the work, indicated at W and carried in a usual headstock 6 and tailstock 7 on a work supporting base member 8 which is reciprocable longitudinally to reciprocate the work relative to the particular wheel 1 or 2 which is in use and while the wheel is rotated in a usual manner; this base member 8 herein being supported on and reciprocated by improved mechanism including a pair of spaced 45 oscillating supporting and feeding rolls 9 disposed between the member 8 and the main frame 5, all as hereinafter more fully described.

Referring more particularly to these rolls 9, it will be noted that each of the same is of generally crescent-shaped cross section, and that the

same are oppositely disposed relative to one another, so that longitudinally extending slots or openings 10 between the opposite longitudinal edges 11 on different rolls face outwardly and away from one another in all positions thereof. It will also be observed that these members 9 are of substantially the width of the member 8 but of somewhat less width than an intermediate supporting member 12 which is disposed beneath and supports the member 8; the member 8 being adjustable angularly relative to this member 12 and rotatable on a pivot 12a and clamps 8a holding the table 8 fixed on table 12, after any angular adjustment, as for example, when grinding tapers or the like. Attention is also directed to the fact that each of the members 9 has a plurality of transversely disposed series of gear teeth 14 intermediate the ends of the member 9 and between smooth peripheral end portions 15 on the latter disposed above the roots of the teeth 14. These portions 15, as shown in Figure 2, thus act to provide oscillating load bearing surfaces co-operating with flat surfaces 16 on the bottom of the member 12 and on opposite sides of a rack member or members 17, suitably removably attached to the member 12 and preferably embedded therein; the teeth on this rack member being adapted to cooperate with the teeth 14 on the upper ends of the members 9 when the latter are rotated, as hereinafter described. Further, it will be noted that while the teeth 14 may extend continuously around the outer periphery of the members 9, they are preferably, as herein, provided in a pair of spaced series adjacent the extremities of these members. Moreover, it will be noted that the stationary bed frame 5 has a plurality of series of stationary rack teeth 18 thereon, preferably also on a removable rack similar to rack 17 and adapted to cooperate with the teeth 14 on the lower ends of the rolls 9, and also flat surfaces 18a corresponding to the surfaces 16 and adapted to support the load carrying surfaces 15 on the rolls.

Thus, it will be evident that when, for example, the members 9 are rotated to the right about their longitudinal axes by means hereinafter described, the support 12 and the work W thereon will be fed longitudinally to the right. Further, the support 12 will move from the intermediate position thereof shown in full lines in Figure 1, first to the extreme right hand dotted line position indicated in Figure 3, and then back through said intermediate position to the left hand position indicated in full lines in the latter figure. In these positions, the member 12 is not only always supported on the two rolls 9, but the latter roll to the right or left as the support 12 moves to the right or left. Moreover, note that not only do the rolls thus, in effect, automatically widen the support as necessary, but, in each position of each roll provide a support for the support 12 at diametrically opposite points on each roll.

Attention is also directed to the fact that the rack 17 on the upper member 12 is suitably spaced at its ends inwardly from downwardly projecting end skirt portions 19 at the ends of the member 12, herein having usual troughs 20 along their upper edges. Further, cooperating inwardly and then upwardly curved end enclosing members 21 are also provided at opposite ends of the top of the frame 5 at points adjacent the outer extremities of series of teeth 18 thereon; these members 21 also preferably having suitable grooves 22 at their lower outer ends, and having their inner ends 23 substantially spaced inwardly

from the skirt portions 19 in the mid-position of the parts illustrated in Figure 1, and the upper extremities of these ends 23 only slightly vertically overlapping the lower extremities of the end skirt members 19. At each end of the two cooperating rolls 9 a stationary enclosing member 24 is also provided fixed to the bed frame 5 and extending up approximately to the bottom of the member 12 inside shorter depending cooperating side enclosing members 25 depending from the longitudinal edges of the member 12; cooperating ways 24a being formed at the top of the members as usual in such machines. Longitudinal troughs 26 are also provided along the top longitudinal edges of the member 12 and corresponding to and communicating with the troughs 20 heretofore described, while suitable bottom troughs 27 are also provided outside the members 24 and at the bottom thereof.

Thus it will be noted that an enclosing chamber 9a for the rolls 9 and their operating mechanism is provided between the top of the base 5 and the member 12, so that during operation, the rolls and their cooperating racks on the members 12 and 5 will be protected. Moreover, it will be evident that as the work support moves to the right or left beyond the ends of the base 5, the rolls 9 will be able to move into and out of the space above the upper ends 23 of the side members 21 and above these members, due to the slots 10 in the rolls, as clearly appears from Figure 3, all in such manner as to enable the rolls to perform their supporting function at different points laterally on the bed frame 5 as the rolls travel laterally with the work support relatively to the bed.

Controlling the various mechanisms on the work support is also any suitable controlling mechanism, the same, however, herein being disposed in an improved arrangement relative to the roll members 9 and in such manner as not in any way to interfere with the free movement of these members. Thus, the usual hand wheels 28 and 29 for the work table have usual operating and controlling shafting and gearing, but the shafting is disposed between the members 21 and adjacent the tops of the same and also extended through and journaled in the side members 24, while being provided with any form of usual operative connection leading to the elements to be controlled thereby. Moreover, it will be noted that a rack member 30, which, as usual, is movable with the work support, is herein carried by and depending beneath the member 12 and disposed between one of the members 24 and the adjacent end of one of the rolls 9 so that it may cooperate as usual with the gears of the adjusting mechanism operated by the hand wheels. Here also a usual lever operating rod 31 is carried on the outside of one of the side members 25 and at the bottom thereof in such manner that usual spaced stops 32 on this member 31 may reversely swing a usual upstanding reversing lever 33, herein carried on a shaft 33a between the rolls 9 and also journaled in the members 24, in such manner as to control the connection of a usual clutch mechanism 34 and thereby effect reverse rotation of the rolls 9; power herein being transmitted to the rack 30 in the chamber 9a by suitable driving gearing 35 and other cooperating driving gearing 35a from a power shaft 36 driven from any suitable motor (not shown) or, if desired, from suitable shafting. Obviously, the driving and controlling mechanisms may assume widely different forms, ample space being pro-

vided for the necessary connections within the chamber 9a without in any way interfering with the rolling movements of the rolls.

In the operation of the device, it will be noted that the rolls 9, while maintained in the same spaced relation to one another, move laterally with the work support or table as they rotate during each lateral movement of the latter. Thus, they thereby provide, in effect, an extensible support for this table movable laterally therewith in either direction; the rolls 9 in the extreme right hand position of the table, shown in dotted lines at the right in Figure 3, assuming the dotted line positions indicated therein, while in the extreme left hand position of the table, indicated in full lines in that figure, the rolls 9 assume the positions shown in full lines. Obviously, the length of travel of the work support or table may be varied as desired between these limits and the feed, as usual in such machines, may be effected by either hand or power.

The rollers, which support the upper bed or carriage from the lower bed and which are provided at each end portion with an arcuate cylindrical load-supporting surface, are of substantial diameter in relation to the length of the lower bed, so that, in a complete traverse of the carriage from the full line position of Fig. 3 to the dotted line position of said figure, each roller rotates through less than one revolution.

The roll members are in the approximate form of crescents, the open sides being disposed toward the respective ends of the machine. The driving connections for traversing the carriage are arranged at one end of the machine where one of the rolls by reason of its open side clears these connections as well as the member 21 at that end of the machine. On each roll member, the series of gear teeth for engaging the carriage and the series of gear teeth for engaging the lower bed are in a median longitudinal plane whereas the cylindrical bearing portions having end parts engageable respectively with the carriage and the bed are disposed in vertical planes extending lengthwise of the machine on opposite sides of the median plane above mentioned. The gear teeth provide operative connections to the carriage and bed, whereby the roll members are maintained at all times in a predetermined relationship to the carriage and bed. The gear teeth provide means for actuating the roll members so as to shift the support for the carriage as the latter moves in either direction toward an overhanging position.

As a result of my improvements, the previous difficulties with the so-called "see-saw" condition and the wear incident thereto or arising therefrom, are effectually overcome, due to the provision of adequate supports for the work table at each end of its travel and the elimination of the previous unbalancing of the mechanism at the ends of the table travel. Attention is also directed to the fact that my improved construction makes possible an increased range of feeding movement of the work table for a machine of a given length. With bearing rolls 9, an extremely rugged and long wearing construction is produced as compared with the sliding frame of the prior art, and one which requires only a mini-

num of attention to oiling. It will also be noted that the structure is such that both the rolls and the operator are well protected. While illustrated only as applied to the longitudinal feed of a grinder, my improved structure may also be used for the cross feed if desired. It will also be apparent that the same may be used on other tools than grinders. These and other advantages of my improvements will, however, be clearly apparent to those skilled in the art.

While I have herein specifically described one embodiment which my invention may assume in practice, it will be understood that this form is shown for purposes of illustration, and that my invention may be modified and embodied in various other forms without departing from its spirit or the scope of the appended claims.

What I claim as new and desire to secure by Letters Patent is:

- 20 1. In a machine tool, a bed, a reciprocable bed movable relative thereto, oscillating supporting rolls between said beds and actuated by movement of said reciprocable bed for shifting the support for the latter in either direction of movement thereof, upstanding end members on said first mentioned bed, and chamber forming means in said rolls in which said last mentioned means are receivable during oscillation of said rolls.
- 25 2. In a grinder, a bed, a reciprocable bed movable relative thereto, grinding mechanism on said first mentioned bed, a work support on said reciprocable bed, actuating means for reciprocating said reciprocable bed, supporting rolls for said reciprocable bed between said beds and actuated by said actuating means to shift the support for said reciprocable bed in the direction of movement of the latter, enclosing means for said rolls including upstanding end members, and chamber forming means in said rolls receiving said upstanding members as said rolls are oscillated.
- 30 3. In a grinder, a bed, a reciprocable bed movable relative thereto, grinding mechanism on said first mentioned bed, a work support on said reciprocable bed, actuating means for reciprocating said reciprocable bed between said beds and actuated by said actuating means to shift the support for said reciprocable bed in the direction of movement of the latter, enclosing means for said rolls including upstanding end members, chamber forming means in said rolls receiving said upstanding members as said rolls are oscillated, and controlling mechanism for said grinding mechanism including operative connections disposed between said rolls and said upstanding members.
- 35 4. The combination with a machine tool bed, and a carriage spaced upwardly from the bed and intended to be traversible to positions in which it overhangs the bed substantially at the respective ends of the latter, of approximately crescent-shaped roll members interposed between the carriage and the bed, the open sides of the roll members being disposed toward the respective ends of the machine, and driving connections for traversing the carriage arranged adjacent one end of the machine in a location in which the open side of the adjacent roll member permits the clearing thereof as the carriage is traversed.

JOHN JESIONOWSKI.
